UNITED STATES PATENT OFFICE.

ROBERT CEDERSTROM, OF ST. LOUIS, MISSOURI.

DESIGN FOR A MEASURING-VESSEL.

SPECIFICATION forming part of Design No. 23,383, dated June 19, 1894.

Application filed May 21, 1894. Serial No. 512,016. Term of patent 7 years.

To all whom it may concern:

Be it known that I, ROBERT CEDERSTROM, of the city of St. Louis, State of Missouri, have invented a new and original Design for 5 a Measuring-Vessel, for the term of seven years, of which the following is a full, clear, and exact description, reference being had to the accompanying drawings, forming a part hereof.

- o Figure 1 is a side elevation of a measuring vessel, showing my design, and Fig. 2 is a sectional side elevation of the same.

The leading feature of my design consists in the body 1 formed somewhat of the contour 5 of two truncated cones 2 and 3 united at the point of their smallest diameters, and an annular angular projection 4 upon the exterior of said body at said point. Upon the interior of said body at said point, there is a horizontal abutment 5, the upper and lower outlines 10 of which are straight and parallel. The upper and lower ends of said body have each

an annular rounded projection, or bead, 6 upon the exterior of said body. Vertically aligned projections 7 having pointed free 25 ends are formed on said body 1, adjacent to each end thereof, and the outer portions of these projections are straight and in horizontal alignment with the adjacent end of the body, while the inner portions of said projections are curved. 30

A curvilinear body 8 extends vertically from a point adjacent the upper end of the body 1 to a point beneath the center of the length thereof, and is bowed outward. 35

What I claim is—

The design for a measuring vessel, as herein shown and described.

In testimony whereof I affix my signature in presence of two witnesses.

ROBERT CEDERSTROM.
